TABLE

William James Bargen, Waukegan, Ill.

Application December 29, 1950, Serial No. 13,627

Term of patent 14 years

(Cl. D33—14)

To all whom it may concern:

Be it known that I, William J. Bargen, a citizen of the United States of America, residing at Waukegan, in the county of Lake, and State of Illinois, have invented a new, original, and ornamental Design for a Table, of which the following is a specification, reference being had to the accompanying drawing, forming a part hereof.

In the drawing:

I claim:

The ornamental design for a table, as shown.
WILLIAM JAMES BARGEN.
